UNITED STATES PATENT OFFICE.

LINUS D. ARMSTRONG, OF PROVIDENCE, RHODE ISLAND.

COTTON-PICKER.

1,170,389.

Specification of Letters Patent.

Patented Feb. 1, 1916.

Application filed October 27, 1915. Serial No. 58,280.

To all whom it may concern:

Be it known that I, LINUS D. ARMSTRONG, a citizen of the United States, and resident of the city of Providence, in the county of Providence and State of Rhode Island, have invented certain new and useful Improvements in Cotton-Pickers, of which the following is a specification.

This invention relates to grid bars of the class adapted for use in cotton picking machines and the like, and the object of this invention is to provide such a grid bar having its two opposite working edges beveled, whereby the bar may be reversed edge for edge to bring the fresh working edge into operating position when the first edge has been worn, thereby doubling the working life of the grid bar.

A further object of the invention is to bevel the opposite edges of the grid bar, both in the same direction, so that the bevel on these edges will be substantially parallel one with the other, by this construction the frictional area of the bar over which the motes and foreign substances pass in leaving the cotton is considerably reduced.

A further object of the invention is the provision of trunnions on the opposite ends of each bar whereby when set their working angle may be readily adjusted as desired.

With these and other objects in view, the invention consists of certain novel features of construction, as will be more fully described, and particularly pointed out in the appended claims.

In the accompanying drawings: Figure 1— is a side elevation partly in section illustrating a gang of my improved grid bars in operative position also showing the adjusting means. Fig. 2— is a section on line 2—2 of Fig. 1, showing one end of a grid bar as pivoted in the frame and the fingers or pins of the sliding plate as engaging the grid bars for the purpose of adjustment. Fig. 3— is a perspective view of one of the grid bars. Fig. 4— is a perspective view showing a portion of the sliding plate, for adjusting the angle of the grid bars.

Referring to the drawings, 10 designates one side of a double frame which is supported between the side walls of the picking machine by means of the bolts 11 and 12. This frame is provided with spaced apart notches 13 in its upper edge, see Figs. 1

and 2, for the purpose of receiving the grid bars, presently described. This frame is also provided with a long slot 14 which runs substantially in line with and on the general curve of that on which the grid bars are set, this frame is also provided with a downwardly extending ear 15 in which the operating handle is pivoted at 16, see Fig. 2. The grid bars 17 are formed of flat stock 65 which is of a width much greater than its thickness both ends of each bar is provided with a short trunnion 18. An essential feature of this invention is that the opposite edges of each bar are beveled as at 27 and 28 to a thin edge, so that when one edge has been worn by constant work in the machine, the bar may be reversed edge for edge to present a fresh working edge in place of the worn one, whereby the working life 75 of the bar is doubled. Another feature of this invention is that the angle of the bevels on the opposite edges are substantially parallel with each other. These bars are set spaced apart between the two frames 10 with 80 their trunnions rotatably mounted in the notches 13, and a plate 19 is provided to lay against the frame with its pins or fingers 20 extending through the slot 14 therein to engage the individual grid bars. This plate 85 is also provided with a downwardly extending section of toothed rack 21, which is engaged by the segment 22, pivoted at 16 which segment is provided with an operating handle 23. A bolt 24, is passed through a slot 90 25 in the segment member which permits the movement of the same and which may be readily set up, after adjustment has been made, to firmly retain the plate in adjusted position.

In the operation of this device the grid bars are beveled in the manner above described and their trunnions are inserted in the openings 13 whereby the bars are spaced apart and pivotally mounted between the 100 frames 10. This slide bar 19 with its little fingers 20 is positioned on the side of the frame with the fingers extending through the slot 14 in the frame and engaging the outer ends of the grid bars.

It is found in the operation of picking machines that the cotton passed therethrough varies considerably both in its character, length of staple, and also in the amount of foreign matter it contains, therefore it is found advisable to provide means whereby the opening between the grid bars

may be varied to suit conditions under which the machine is operating, therefore when it is desired to reduce the space between the bars it is only necessary to carry the handle portion 23 to the left until the bars are moved to the desired position after which the nut 26 is set up, and the whole remains set until adjustment is again required.

I have shown and described one form of mechanism for adjusting the angle of the grid bars, but the details of this mechanism may be varied without departing from the spirit and scope of my invention. I have also shown the grid bars as formed with the opposite edges of each beveled thereby making each bar reversible whereby its working life may be doubled and any means for accomplishing this object should be considered as covered by this patent.

I claim:

1. A reversible grid bar comprising a flat bar having both of its opposite edges beveled to a thin working edge.
2. A reversible grid bar comprising a flat

bar having both of its opposite edges beveled on planes substantially parallel to each other and each having a thin working edge, said bar being adapted to be reversed edge for edge.

3. A reversible grid bar comprising a flat bar having both of its opposite edges beveled on planes substantially parallel to each other each having a thin working edge, said bar being adapted to be reversed edge for edge, and means whereby said bar may be rocked to adjust its working angle.

4. A reversible grid bar comprising a flat bar having its opposite edges beveled to a thin working edge, said bar being adapted to be reversed edge for edge, and a trunnion on the end of each bar whereby the same may be rotatably mounted.

In testimony whereof I affix my signature in presence of two witnesses.

LINUS D. ARMSTRONG.
